UNITED STATES PATENT OFFICE.

CHARLES A. HUFFORD, OF INDIANAPOLIS, INDIANA.

MACHINE FOR BULGING CYLINDRICAL SHEET-METAL BODIES.

1,067,115.

Specification of Letters Patent.

Patented July 8, 1913.

Application filed June 12, 1912. Serial No. 703,323.

To all whom it may concern:

Be it known that I, CHARLES A. HUFFORD, a citizen of the United States, residing at Indianapolis, in the county of Marion and State of Indiana, have invented certain new and useful Improvements in Machines for Bulging Cylindrical Sheet-Metal Bodies; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to improvements in machines for bulging cylindrical sheet metal bodies into convex form, as in the production of sheet metal barrels or kindred articles of manufacture.

The object of the invention is to provide a machine which is substantially positive in its action, and by means of which the operation stated may be performed quickly and with facility and accuracy.

An embodiment of the invention is illustrated in the accompanying drawings wherein:

Figure 1 is a central longitudinal section showing the parts of the machine prior to an operation thereof; Fig. 2 is a similar view but showing the machine in operation; Fig. 3 is an end elevation of one of the sectional dies or forming units; Fig. 4 is a developed plan view showing the relations of the die sections to one another when the die is collapsed; Fig. 5 is a similar view but showing the relation of the die sections to one another when the die is expanded.

Similar characters of reference designate corresponding parts throughout the several views.

The operating parts may be supported from a bed 1. In the embodiment shown the machine includes a pair of opposed sectional dies, designated generally by the numeral 2 and simultaneously movable toward and away from one another. Means for operating the dies are provided at each end of the bed. As shown, the die operating means include cylinders 3 and pistons 4 working therein and actuated hydraulically.

Each die 2 comprises die sections 5 of suitable outline which are arranged in an annular path. Said die sections are provided with outwardly directed extensions 7

which are pivoted in slotted ears 7^a disposed radially upon a head 8. The pistons 4 are mounted on rods 9 which pass loosely through central openings in the heads 8 and serve, through intermediate connections to effect axial and pivotal movements of the die sections and thereby to move the dies into and from their operative positions and, at the same time, to expand and collapse them. The intermediate connections between the rods 9 and the die sections may advantageously include sleeves 10 which are mounted loosely on the rods 9, between collars 11 and 11^a fast on said rods, and links 12 which connect each sleeve 10 and the die sections to be operated thereby.

In order to maintain the dies in normally collapsed relation and at the same time to cause the dies to move with the rods when the latter move inwardly, expansive coil springs 13 surround the rods 9 and are arranged between the outer faces of the heads 8 and collars 14 adjacent said heads and fast on the respective rods 9.

The accuracy of the operation of the dies is insured by positively centering and guiding the rods 9 and for this purpose, suitable bearings 15, upstanding from the bed 1, may be provided. It is also preferred, toward the same end, to provide one of the rods 9 with a reduced axial extension 16 and the other rod with a slot or opening 17 to receive said extension, during the movements of the rods to expand the dies.

The cylinder to be shaped is placed between the dies, it being assumed that the latter are retracted as far as possible from one another and that their die sections are in collapsed relation. Thereupon the dies are moved simultaneously and axially toward one another, ultimately passing through the ends of the cylinder. The axial movement of the dies is arrested by the engagement of the heads 8 against the ends of the barrel but the axial movements of the rods 9 continue against the tension of the springs 13, however, and until it is arrested by the engagement of the collars 14 against the heads 8 or by the engagement of said rods against one another. In this last stage of their axial movement the rods 9 are effective, through the agency of the sleeves 10, the collars 11 in the rear of said sleeves, and the links 12, to move the die sections 5 outwardly on their pivots, thereby expanding the dies 2 and causing the latter to bulge the barrel.

Thereupon the movements of the rods 9 are reversed, that is to say said rods are simultaneously retracted; and during the first portion of such retractile movements 5 throughout which the springs 13 hold the heads 8 against the ends of the barrel, the dies are collapsed, the necessary movement of the sleeves 10 with the rods 9 being imparted by the collars 11^a which are immediately 10 in advance of said sleeves. Thereafter, as the outward movement of the rods 9 continues, the collars 11 engage the heads 8 and the dies are positively withdrawn 15 from the barrel, as is obvious.

15 In order that the bulging or changing of the barrel body may be uniform throughout the extent of said body, each die section 5 is preferably provided along its sides with teeth 18 which are constantly in mesh with 20 the teeth of the adjacent die sections, both in the collapsed and expanded condition of the dies. In this way continuous spaces between the die sections, when the dies are expanded, are eliminated; and it follows that 25 the formation of flat longitudinal areas at intervals throughout the barrel body will be prevented and the barrel will be uniformly convex throughout its extent.

Having fully described my invention, I 30 claim:—

1. In a machine of the type set forth, a collapsible die including a head and die sections pivoted thereon, an axially movable rod, a yielding connection between the rod 35 and the head, and positive connections between the rod and the die sections to cause movements of the latter on their pivots consequent to the movements of the rod.

2. In a machine of the type set forth, a 40 collapsible die including a head, die sections pivoted thereon, an axially movable rod, an expansive coil spring interposed between the head and the rod, and link connections interposed between the rod and the die sections to 45 cause movements of the latter on their pivots consequent to movements of the rod.

3. In a machine of the type set forth, a collapsible die including a head, die sections pivoted thereon, an axially movable rod, an 50 expansive coil spring interposed between the head and the rod, a sleeve loose on the rod, collars fast on the rod and between which the sleeve is mounted, and links connecting the collars and the die sections.

55 4. In a machine of the type set forth, a collapsible die including a head and die sections pivoted thereon, an axially movable

rod, a yielding connection between the rod and the head, and link connections between the rod and the die sections to cause movements of the latter on their pivots consequent to movements of the rod. 60

5. In a machine of the type set forth, a collapsible die including a head and die sections pivoted thereon, an axially movable 65 rod passing loosely through the head, and link connections between the rod and the die sections to cause movements of the latter on their pivots consequent to movements of the rod. 70

6. In a machine of the type set forth, an expansible and collapsible die including a plurality of die sections, annularly arranged and mounted for radial movement, each die section having its sides formed with teeth 75 which constantly intermesh with the teeth of the adjacent die sections. 75

7. In a machine of the type set forth, a pair of end opposed expansible and collapsible dies, die operating means including 80 axially movable rods and connections between each rod and a corresponding die to produce axial movements of said dies and also expanding and collapsing movements thereof. 85

8. In a machine of the type set forth, a pair of end opposed expansible and collapsible dies, die operating means including rods which are movable axially and simultaneously in opposite directions, and connections between each rod and a corresponding die to produce axial movements of said dies and also expanding and collapsing movements thereof. 90

9. In a machine of the type set forth, an axially movable rod, a head having an opening through which the rod loosely passes, a plurality of die sections pivoted in the head for radial movement, and link connections between the rod and the die sections. 95

10. In a machine of the type set forth, an axially movable rod, a head having an opening through which the rod loosely passes, a plurality of die sections pivoted in the head for radial movement, link connections between the rod and the die sections, and a resilient connection between the rod and the head. 105

In testimony whereof I affix my signature in presence of two witnesses.

CHARLES A. HUFFORD.
